LINOLEUM FLOOR COVERING OR SIMILAR ARTICLE

Robin F. Jones, Montclair, N. J., assignor to Con-goleum-Nairn Inc., a corporation of New York

Application January 15, 1953, Serial No. 23,148

Term of patent 14 years

(Cl. D92—17)

To all whom it may concern:

Be it known that I, Robin F. Jones, a citizen of the United States of America and a resident of Montclair, county of Essex, and State of New Jersey, have invented a new, original, and ornamental Design for a Linoleum Floor Covering or Similar Article, of which the following is a specification, reference being had to the accompanying drawing forming a part hereof. The figure is a plan view of a linoleum floor covering or similar article showing my new design on a much reduced scale.

The drawing is shaded to show contrast, and the repeat unit of my new design is contained between the two horizontal dot and dash lines and the two vertical dot and dash lines. The characteristic feature of my design resides in the surface pattern of contrasting bars arranged on a jaspe background as shown.

I claim:

The ornamental design for a linoleum floor covering or similar article, substantially as shown and described.
